DESIGN FOR A BOTTLE

Walter Nuckols, Summit, N. J., assignor to Helena Rubinstein, Inc., New York, N. Y., a corporation of New York

Application September 11, 1937, Serial No. 71,576

Term of patent 7 years

To all whom it may concern:

Be it known that I, Walter Nuckols, a citizen of the United States of America and residing at Summit, Union County, New Jersey, have invented a new, original, and ornamental Design for a Bottle, of which the following is a specification, reference being had to the accompanying drawing, forming part thereof.

I claim:—

The ornamental design for a bottle, as shown.

WALTER NUCKOLS.
